[57] **CLAIM**

The ornamental design for an inline fuse holder, substantially as shown and described.

DESCRIPTION

FIG. 1 is a perspective view of an inline fuse holder embodying the present design;

FIG. 2 is an enlarged side elevational view thereof;

FIG. 3 is an enlarged end elevational view thereof;

FIG. 4 is an enlarged elevational view of the side opposite that shown in FIGS. 1 and 2; and

FIG. 5 is an enlarged edge elevational view thereof. The conductor is broken away to indicate indeterminate length.
